UNITED STATES PATENT OFFICE.

CLARK C. WORTLEY, OF CHICAGO, ILLINOIS.

DESIGN FOR A SIGN.

44,394.

Specification for Design.

Patented July 22, 1913.

Application filed May 12, 1913. Serial No. 767,220. Term of patent 7 years.

To all whom it may concern:

Be it known that I, CLARK C. WORTLEY, a citizen of the United States, residing at Chicago, in the county of Cook and State of Illinois, have invented a new, original, and ornamental Design for a Sign, of which the following is a specification, reference being had to the accompanying drawing, forming a part hereof.

The figure is a perspective view of a sign

in accordance with my new design, the upper portion of the device being indicated at 1.

I claim:

The ornamental design for a sign, as shown.

CLARK C. WORTLEY.

Witnesses:

L. HEISLAR,
E. D. STEELE.
